CLAIM

The ornamental design for a partition plate of storage rack, as shown and described.

DESCRIPTION

FIG. 1 is a perspective view of a partition plate of storage rack showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is bottom plan view thereof; and,

FIG. 8 is a reference view of an embodiment the present invention in a shelf configuration.

The broken lines are for the purpose of illustrating the environment of the article only and form no part of the claimed design.
